UNITED STATES PATENT OFFICE.

JOHN L. CARNLEY, OF RUBLE, MISSISSIPPI.

LOCOMOTIVE-HEADLIGHT.

1,082,623.

Specification of Letters Patent. Patented Dec. 30, 1913.

Application filed September 24, 1913. Serial No. 791,596.

To all whom it may concern:

Be it known that I, JOHN L. CARNLEY, a citizen of the United States, residing at Ruble, in the county of George and State 5 of Mississippi, have invented certain new and useful Improvements in Locomotive-Headlights, of which the following is a specification, reference being had to the accompanying drawings.

10 This invention relates to certain improvements in locomotive headlights and has relation more particularly to a device of this general character capable of automatic operation whereby the headlight will be 15 properly turned so as to throw the light to one side when the locomotive to which it is applied is rounding a curve, and the object of the invention is to provide a device of this general character having novel and improved means whereby the support for the lamp is under control of a pendulum.

15 The invention consists in the details of construction and in the combination and arrangement of the several parts whereby 20 certain important advantages are attained and the device is rendered simpler, less expensive and otherwise more convenient and advantageous for use, all as will be herein-after more fully set forth.

25 The novel features of the invention will be carefully defined in the appended claims.

In order that my invention may be the better understood, I will now proceed to describe the same with reference to the accompanying drawings, wherein—

30 Figure 1 is a view in side elevation of a locomotive headlight constructed in accordance with my invention, the adjacent portion of the locomotive to which it may be 35 attached being indicated by dotted lines; Fig. 2 is a horizontal sectional view taken through Fig. 1 with the lamp omitted; and Fig. 3 is a transverse vertical section taken through Fig. 1.

40 As disclosed in the drawings, 1—1 denote spiced frame plates disposed in horizontal planes and suitably connected one with the other by the posts or uprights 2—2 the frame afforded thereby being adapted to be positioned at the space now generally employed 45 for locating the headlight on a locomotive.

45 Mounted in the plates 1—1 and adjacent the forward marginal portions thereof at substantially their centers is the vertical shaft 3 having fixed thereto the table or 50 platform 4, such table or platform 4 being

preferably circular in form and projecting a predetermined distance beyond the plates 1—1 and produced on such projected portion 5 of the table or support are the uprights 6—6 between which is adapted to be positioned the lamp 7 proper, said lamp being held against displacement by the clamping bar 8 coacting with the uprights 6—6 in a manner which is believed to be well known and a further detail thereof is thought to be unnecessary as this arrangement forms no particular feature of my present invention.

To the rear of the platform or table 4 and in alinement with the table 3 and suitably secured in the frame plates 1—1 is the vertically disposed rod 9 which is adapted to serve as a fulcrum for the lever member 10, such lever member 10 having produced at a predetermined point intermediate its length the elongated opening 11 extended longitudinally of the lever and through which the rod 9 is adapted to pass. The forward end portion of the lever is reduced, as at 12, and such reduced portion is so directed as to loosely project through an opening 14 produced in the table or platform 4 at a point substantially central of its radius, such opening 14 being positioned in alinement with the shaft 3 and the rod 9 when the lamp is in position to direct its rays directly forward of the locomotive. In the opposite end portion of the lever member 10 is produced a longitudinally directed elongated opening 15 through which projects the pendulum bar 16 which bar is swingingly supported from the forwardly projecting arm 17 carried by the upper extremity of the upright 18 supported in position by the frame plates 1—1 and disposed in alinement with the shaft 3, herein-before referred to. To the lower extremity of the pendulum bar 16 is affixed the weighted mass 19, such weighted mass being preferably composed of a suitable member formed to afford an elongated body with the opposite faces thereof flattened and disposed in parallel planes with the connection between such mass 19 and the pendulum bar 16 being at substantially the center of such mass, 100 for purposes which are believed to be clearly apparent.

105 It is thought to be obvious that upon the locomotive taking or rounding a curve the mass 19 will serve automatically to maintain the pendulum bar 16 in vertical position with the result that the table or sup-

port 4 will be caused to rotate through the medium of the lever member 10 in a direction corresponding to the curve of the roadway. The extent of the axial movement of the table or support 4 being dependent upon the extent or degree of leaning of the locomotive together with the length of the pendulum bar 16. It is therefore thought to be obvious that the turning of the table or 10 platform 4 will cause the lamp 7 to properly illuminate the roadway as the locomotive is making a turn.

In order to prevent the weighted mass or body 19 from undue lateral movement or 15 vibration as would otherwise tend to interfere with the successful operation of the device, I have such body 19 mounted to travel between the parallel guide plates 20, the space between such plates being but 20 slightly in excess of the transverse diameter of the body 19. The speed of the locomotive in transit tends to cause the weighted mass or body 19 to bear against or contact with the rear of the guide plates 20 and, in 25 order to eliminate the resultant friction, I suitably mount in such rear plate 20 a plurality of vertically disposed rollers 21 serving as an anti-friction means to relieve the weighted mass or body 19 of any possible 30 frictional resistance. The forward guide plate 20 serves as a means for limiting the downward movement of the lever 10, such lever being adapted to rest upon the upper edge thereof.

From the foregoing description, it is thought to be obvious that a headlight for locomotives constructed in accordance with my invention is of an extremely simple and comparatively inexpensive nature and 40 is particularly well adapted for use by reason of the convenience and facility with which it may be applied in position and by reason of the certainty with which the lamp proper may be caused to direct its rays 45 along the roadway at all times and it will also be obvious from the foregoing description that my invention is susceptible of some change and modification without material departure from the principles and 50 spirit thereof and for this reason I do not wish to be understood as limiting myself to the precise arrangement and formation of the several parts herein shown in carrying out my invention in practice.

55 I claim:

1. A device of the character described comprising spaced frame plates, a vertically disposed shaft mounted in said frame plates, a table fixed to said shaft and having a portion projecting beyond the frame plates, a post carried by the frame plates and in alignment with the shaft, a standard projecting upwardly from the frame plates and provided with an inwardly directed arm 60 disposed in a plane in alignment with the

plane occupied by the shaft, a pendulum bar swingingly supported by the arm, a weighted mass secured to the lower end portion of the bar, a lever provided with an opening intermediate its length through which the bar extends and having one of its end portions in pivotal engagement with the table and having a second opening in its opposite end portion through which the pendulum bar passes, and guide plates disposed at opposite sides of the weighted mass to hold the same against transverse movement. 70

2. A device of the character described comprising spaced frame plates, a vertically disposed shaft mounted in said frame plates, a table fixed to said shaft and having a portion projecting beyond the frame plates, a post carried by the frame plates and in alignment with the shaft, a standard projecting upwardly from the frame plates and provided with an inwardly directed arm disposed in a plane in alignment with the plane occupied by the shaft, a pendulum bar swingingly supported by the arm, a weighted mass secured to the lower end portion of the bar, a lever provided with an opening intermediate its length through which the bar extends and having one of its end portions in pivotal engagement with the table and having a second opening in its opposite end portion through which the pendulum bar passes, guide plates disposed at opposite sides of the weighted mass to hold the same against transverse movement, and anti-friction means carried by the rear guide plate adapted to coöperate with the weighted mass. 80

3. A device of the character described comprising spaced frame plates, a vertically disposed shaft mounted in said frame plates, a table fixed to said shaft and having a portion projecting beyond the frame plates, a post carried by the frame plates and in alignment with the shaft, a standard projecting upwardly from the frame plates and provided with an inwardly directed arm disposed in a plane in alignment with the plane occupied by the shaft, a pendulum bar swingingly supported by the arm, a weighted mass secured to the lower end portion of the bar, a lever provided with an opening intermediate its length through which the bar extends and having one of its end portions in pivotal engagement with the table and having a second opening in its opposite end portion through which the pendulum bar passes, and guiding plates disposed at opposite sides of the weighted mass to hold the same against transverse movement, the said lever being in contact with the upper edge of the forward guiding plate. 90

4. A device of the character described including a table mounted for axial movement and adapted to support a lamp, a rock 100

lever having one extremity in pivotal engagement with the table, a suitably supported pendulum bar in engagement with the opposite end portion of the lever, a 5 weighted mass carried by the pendulum bar, guiding plates disposed at opposite sides of the weighted mass to hold the same against transverse movement, and anti-friction means carried by one of such plates and

adapted to contact with the adjacent surface 10 of the mass.

In testimony whereof I hereunto affix my signature in the presence of two witnesses.

JOHN L. CARNLEY.
